UNITED STATES PATENT OFFICE.

EDWARD J. VON PEIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

MULTIPLE CASH-REGISTER.

1,153,360.

Specification of Letters Patent. Patented Sept. 14, 1915.

Application filed September 2, 1911. Serial No. 647,366.

To all whom it may concern:

Be it known that I, EDWARD J. VON PEIN, a citizen of the United States, residing at Dayton, in the county of Montgomery and 5 State of Ohio, have invented certain new and useful Improvements in Multiple Cash-Registers, of which I declare the following to be a full, clear, and exact description.

This invention relates to accounting machines and principally to the recording mechanism thereof.

In accounting machines as heretofore constructed mechanism has been provided, which coöperates with certain manipulative 15 devices for rendering a check issuing mechanism operative, but the great objection to accounting machines so constructed is that it is impossible to place the check issuing mechanism under the control of any of the 20 other manipulative devices of the machine without reconstructing the machine.

It is a principal object of this invention to provide such machines with mechanism, which at the will of the operator, may be so 25 adjusted as to render operative the check issuing mechanism as an accompaniment to the entering in the machine of any one of a plurality of transactions.

Another object of this invention is to provide 30 an impression mechanism whereby duplicate impressions can be made upon a check and the check perforated between the impressions. This impression mechanism may be provided with a knife for severing the check strip into checks, which knife is rendered inoperative when the first impression is taken upon any check.

In a great many accounting machines now upon the market a record strip is provided 40 upon which is recorded the various entries in the machine, but in many instances this record strip is inaccessible to the operator and he cannot enter memoranda thereon.

45 It is a further object of this invention to provide such machines with a movable frame carrying the platen over which the record strip passes, which frame is normally in position to have entered upon the record 50 strip any suitable memoranda, but is adapted then to be moved into position to have recorded in alinement with the written memorandum, the entry made in the machine.

55 Another object of this invention is to pro-

vide an operating mechanism under the control of separate and independent manipulative devices, which manipulative devices require certain sequences of operation.

Another object of this invention is to provide 60 a plurality of independent means for controlling the extent of movement of a differentially movable element, which means are constructed so that when one of said means is positioned to control the differentially movable element, the rest of said means will be rendered inoperative for this purpose.

Another object of this invention is to provide 65 interlocking mechanism between an adjustable manipulative device and a series of keys, which manipulative device renders one or more of the keys inoperative, depending upon the position of said manipulative device.

75 With these and incidental objects in view the invention consists in certain novel features of construction and combinations of parts, the essential elements of which are set forth in appended claims, and a preferred 80 form of embodiment of which is hereinafter shown with reference to the drawings which accompany and form part of this specification.

Figure 1 is a side elevation of a machine 85 of the type shown in Patent No. 938,527 granted Nov. 2, 1909, to E. J. Von Pein and to which the various improvements embodying this invention have been applied. Fig. 2 is an elevation of the machine, showing 90 the recording mechanism and looking in the opposite direction from that of Fig. 1. Fig. 3 is an enlarged view of one of the actuating pawls of the ink ribbon feeding mechanism and its companion segmental plate. Fig. 4 is a central transverse sectional view of the machine. Fig. 5 is a view similar to Fig. 4 but looking in the opposite direction. Fig. 6 is a partial rear elevation showing the mechanism for setting the drawer releasing plunger and also the adjustable devices for controlling the check issuing mechanism. Fig. 7 is a partial front elevation showing one bank of keys and an adjustable lever which controls a plurality of accounting 100 devices. Fig. 8 is an enlarged side elevation of the check issuing mechanism. Fig. 9 is a top plan view of the impression mechanism. Fig. 10 is a side elevation of the 105 gearing for the operating mechanism. Fig. 110

11 is a partial top plan view of the oscillatory frame upon which the record strip is mounted and operating mechanism therefor. Fig. 12 is a detail view of the mechanism for oscillating the frame carrying the record strip. Fig. 13 is a detail view of the mechanism for moving the frame carrying the record strip against the type carriers for the purpose of taking an impression therefrom. Fig. 14 is a partial side elevation and Fig. 15 a front elevation of the adjustable lever for positioning the accounting devices or totalizers. Fig. 16 is a detail view of a link which forms a part of the mechanism for controlling the check issuing device. Figs. 17, 18 and 19 are detail views of the locking plates, which coöperate with the bank of special keys. Fig. 20 is a diagram showing the interlocking lever positions and clerks' keys.

Described in general terms the machine comprises a plurality of accounting devices, such as totalizers, any one of which may be brought into coöperative relation with a set of actuators by an adjustable element, these actuators being controlled by manipulative devices or keys. A special bank of keys is provided with suitable interlocking mechanism between the bank and the adjustable element or lever, so that when certain accounting devices are brought into coöperative relation with the actuators, certain of the keys are released, while others remain locked, and when the other accounting devices are brought into coöperative relation with the actuators, the keys that were locked formerly become unlocked and the keys that were formerly unlocked became locked. In certain positions of the adjustable lever a differentially movable element will be controlled thereby, while in other positions this element will be controlled by the special keys. This differential element is suitably connected to digit carriers, such as an indicator and a type wheel, and also to a plunger which is positioned by the movement of said element for the purpose of releasing or exposing any one of a plurality of cash receptacles.

50 After one of the totalizers or accounting devices is brought into coöperative relation with the actuators and the proper keys depressed, an operating handle is turned to enter the transaction in the totalizer which has been previously positioned by said operating lever. This operating handle is locked and is released only by the operation of the adjustable lever and the depression of one of the special keys.

60 Suitable indicators are provided for indicating the kind and the amount of the transaction entered in the accounting device or totalizer. A recording mechanism is also provided, which mechanism comprises a record strip and a check strip, upon each of

which are recorded the transaction entered in the positioned totalizer. The record strip is normally in position to have entered thereon a memorandum of the transaction to be entered in the totalizer, and the frame carrying the record strip is oscillated at the operation of the machine, into a position adjacent the type carriers of the recording mechanism, so that by the further operation of the machine the entry entered in a totalizer will be recorded upon the record strip. The check strip is arranged to have duplicate impressions made thereon and to be perforated between these impressions, after which the check will be severed from the remaining portion of the check strip. This check issuing mechanism is constructed to be disabled or enabled at the will of the proprietor by the adjustment of certain manipulative devices which are accessible to the proprietor or some authorized person.

A brief outline of the parts of the patented machine which coöperate with the present improvements will be given, and for a further description of the machine, reference may be had to the before mentioned patent to Von Pein, also to the Cleal and Reinhard patent issued April 13, 1897, No. 580,378.

The keys 1 (Fig. 4) of each bank of keys are latched in their depressed positions by means of a detent 2 and a retaining bar 3. Each bank of keys controls the differential movement of a segment 4, which is loosely mounted upon a rock shaft 5, and is driven by a cam 6 secured to that rock shaft. The segment of each bank of keys meshes with an intermediate gear 8, which is secured to one of a series of nested sleeves 9 that surround a shaft 10. These sleeves 9 carry at their outer ends actuators 11 which are in the form of segments, one segment only being shown (Fig. 1). Each of the intermediate gears 8 mesh with a gear 12 secured to an indicator 13, loosely mounted upon a rod 14, the latter being secured in the side frames 15 of the machine.

Each of the segments 4 is provided with a stud 16, which plays in an elongated slot 17 formed in an arm 18, the lower end of which is connected to one of a series of sleeves 19 that surround a shaft 20. These sleeves extend toward the right hand side of the machine and are provided with segments, not shown, which adjust type carriers 21 (Figs. 2 and 7) as is well known in the art and fully explained in an application of E. J. Von Pein, No. 498,548, filed May 26, 1909.

A lever 22 (Fig. 1), which is adjustable to a plurality of positions, is loosely mounted upon the rock shaft 5 and has a segmental gear portion 24, which meshes with a segmental rack 25 secured to a shaft 26, which is suitably mounted in the machine

frame 15. The segment 25 has attached thereto a larger segmental rack plate 27, which meshes with a pinion 28 secured to a drum 29, carrying a plurality of totalizers 5 or accounting devices 30. This drum 29 is mounted in a frame 31, which is suitably guided at its upper and lower ends, the upper end thereof being provided with a roller 32, which projects into a cam slot 33 in a 10 lever 34, that is pivotally mounted upon the shaft 10. The lever 34 is provided with a roller 35, which projects into a cam groove 36 formed in a disk 37 secured to a shaft 38, which is one of the main operating shafts 15 of the machine and receives a complete rotation at each operation of the machine. The shape of the cam groove 36 is such that at each operation the frame 31 carrying the totalizer drum 29 will be elevated, carrying 20 the totalizer into engagement with the actuators 11, as is well known in the art.

The lever 22 at its upper end has pivotally mounted thereon a pinch lever 39 (Figs. 1 and 14) which is of a bell crank formation. 25 The horizontal portion of this bell crank lever 39 normally rests upon the upper end of a slide 40 which is connected to the lever 22 by parallel links 41. This slide 40 is provided with the inverted L-shaped block 30 42 (Fig. 15), the horizontal portion of which rests upon the outer edge of a plate 43 (Fig. 1), which plate is carried by arms 44 that in turn are suitably pivoted to one of the side frames 15 of the machine, and 35 which arms at their free ends are connected by slot and pin connection 45 and 46 respectively. The uppermost one of the arms 44 is secured to a shaft 47 which at its inner end has secured thereto a rearwardly extending arm 48 (Fig. 5), the free end of said arm 48, being adjacent, when the machine is at rest, to a notch 49 formed in a disk 50 secured to the shaft 38. The arm 48 and the parts connected therewith are held 40 in the position shown in Figs. 1 and 5 by a spring 51, which is connected to the arm 48 and to one of the frames 15. From this description it will be seen that upon the operation of pinch lever 39, the slide 40 will 45 be depressed, by which movement the arms 44 will be rocked through intervention of the plate 43. The rocking of the uppermost arm 44 will carry the free end of the arm 48 into the notch 49 of the disk 50 and therefore 50 by prevent the rotation of the shaft 38 until the arm is returned to its normal position by the release of the pinch lever. If an attempt is made to operate the pinch lever 39 during the rotation of the shaft 38, the free 55 end of the arm 38 will contact with the periphery of the disk 50 and prevent the operation of the pinch lever. The upper edge of the horizontal portion of the block 42 normally rests in notches 52 in a plate 53, 60 which is secured to the left hand side frame

15 so as to prevent the accidental displacement of the lever 22 and the totalizers positioned by said lever.

Interlocking mechanism.—The machine is provided with nine totalizers 30 carried by 70 the drum 29 whereby any one of the totalizers may be moved into operative relation with the actuating segments 11 by an adjustment of the lever 22. Totalizers brought into cooperative relation with the actuating 75 segments in the six upper positions of lever 22 are shown as assigned to separate clerks, while the other three totalizers accumulate separately special transactions such as “charge,” “received on account” and “paid 80 out.”

As shown in Fig. 7, the keys of the special bank include eight keys for clerks and a cash key. It frequently happens in business 85 establishments that on busy days they employ extra clerks who cannot be accommodated with individual totalizers in the register. This machine is so constructed that entries made by these extra clerks may be entered on a single totalizer, though separate clerks' keys are provided for three such extra clerks. 90

The diagrammatic Fig. 20 shows the general scheme of interlocking devices between the clerks' keys and the lever positions. In this figure the keys of Fig. 7 are indicated by circles having letters inside them and the lever positions are indicated by squares also having designating characters. It will be seen that the five upper lever 95 positions have the same character as the five upper keys. The lines connecting certain of the lever positions with certain of the keys are intended to indicate the interlocks between the lever positions and the keys. That is, any lever position and any key which are connected by a line on this figure may be operated together, but the remaining lever positions and keys cannot be so operated. For example, key “A” may be operated in connection with lever position 100 “charged” but cannot be operated in connection with the “extra” lever position. The cash key may be operated in connection with any of the five upper lever positions 105 but not with any of the four lower lever positions. It may be noted that the braces connecting the three lower lever positions are intended to indicate that these three positions are similar, that is, that any of the 110 clerks' keys A to P may be operated in connection with any one of the three lower lever positions. It will be understood that the main object of this interlocking construction is to obtain a complete indication and 115 printed record of the transaction. If the lever might be set to one of the five clerks' positions and one of the five clerks' upper keys was pressed there would be no object 120 in printing and indicating one of the two 125

things. However, by providing a cash key in the clerk's bank and interlocking it with the five upper positions of the lever a double indication and printing may be obtained. 5 That is, for example, if a charge transaction is made by any one of the clerks, the lever is set to the charge position and the proper clerk's key depressed. This will cause printing and indicating of both the kind of transaction and the clerk making it. There is 10 provided a single differential element operating the clerk's indicator and type carrier and this is constructed to be controlled under certain conditions by both the adjustable lever 22 and the clerks' keys. In the 15 five upper positions of the lever it controls the movement of the differential element, but the three lower clerks' keys also control movement of this element. Therefore if 20 one of these clerks' keys, L, M or P is operated, the differential element will cause the printing and indicating of the clerk's letter. On the other hand if the cash key is 25 operated in connection with one of the five upper lever positions, then the differential element is controlled by the lever positions and again prints the proper clerk's letter. It will be noted from a study of Fig. 20 that any one of the clerks' keys L to P 30 inclusive may be operated in connection with the "extra" totalizer position or with any one of the three special transaction totalizer positions. That is, for a cash transaction made by these extra clerks the 35 extra totalizer would be added to and the indicator and the printing device would show that a cash sale had been made by one of these three extra clerks. If a special transaction is made by one of these three 40 clerks the lever 22 is moved to bring the corresponding totalizer into position for operation. If one of the regular clerks A to K makes a cash sale he sets the lever 22 to his position and presses the "cash" key of 45 the clerk's bank. Thus the item is added on his particular totalizer and the indicator and the printing device show that the particular clerk made a cash sale. If one of the regular clerks A to K enters a special transaction 50 in the machine he will press the corresponding one of the five upper clerks' keys and set the lever 22 to the proper one of the three lower positions. It will readily be seen from Fig. 20 that these separate 55 examples are all possible with the interlocking devices of the diagram and that these devices prevent misoperation of the lever and the clerks' keys. The construction for accomplishing this locking out of the various keys depending upon the accounting device in operative relation with the actuators 60 will now be described.

The shaft 26 which is secured to the segmental rack plate 25, which meshes with the 65 segmental portion 24 of the adjustable le-

ver 22 has secured thereto between the said lever and the bank of special keys, a plate 54 having a cam groove 55 therein, as shown in Figs. 5 and 7. Extending into this cam groove 55 is a roller 57 on the horizontal 70 arm 56 of a bell crank lever. This bell crank lever is pivoted upon a shaft 58 suitably mounted in the machine frame, and the vertical arm 59 of said lever is provided at its extreme upper end with a flange or offset 60. 75 The cam groove 55 is composed of two circular portions of different radii from the center of the shaft upon which the cam plate is mounted, and these portions of the cam are connected by an inclined portion, as 80 fully shown in Fig. 5. When any one of the five regular clerks' accounting devices is positioned to be actuated, the roller 57 plays in the circular portion of the cam groove 55 of less radius and the offset 60 of 85 the bell crank will occupy the position shown in section in Figs. 17, 18 and 19, relative to locking plates 61, 62 and 63, in which position the plates 62 and 63 will be prevented from being elevated because of 90 the offset 60 resting in notches 64 and 65 of the plates 62 and 63, respectively. Key pins 66 of all of the clerks' keys actuate the plate 62, while only the five keys assigned to the regular clerks actuate the plate 63. The key 95 pin 66 of the "cash" key is the only one actuating the plate 61. In the sixth position of the lever from the top the inclined portion of the cam groove 55 will engage with the roller 57 of the bell crank, slightly rocking 100 said bell crank and thus carrying the offset 60 into the position shown by the full lines in Figs. 17, 18 and 19. It will be seen that in this position of the bell crank the offset 60 will lock the plates 61 and 63 which 105 are actuated by the five upper clerks' keys and the "cash" key, leaving the plate 62 which cooperates with the three lowermost clerks' keys free to be operated. When the lever is moved into any of its three lower 110 positions, the roller 57 passes into that portion of the cam groove having the greater radius and rocks the bell crank so as to carry offset 60 into the position shown by the dotted lines in Figs. 17, 18 and 19, in 115 which position the plate 61 will be locked, leaving the plate 62 which cooperates with all of the clerks' keys and plate 63 which cooperates with the five uppermost clerks' keys 120 free to be elevated. These plates 61, 62 and 63 are attached to one of the machine frames 125 by pins 67, which extend through slots 68 of said plates, as shown in Fig. 5.

From this description in connection with diagrammatic Fig. 20, it will be seen that when the lever is in any one of its five upper positions all of the clerks' keys are locked leaving only the "cash" key free to be operated; while said lever is in its sixth position, the three lowermost of the clerks' keys, 130

that is L, M and P are free to be operated, while the "cash" key and the five uppermost ones of the clerks' keys are locked; and in the three lowermost positions of the lever 5 all of the clerks' keys are released and the "cash" key locked.

Machine releasing mechanism.—It has previously been said that the operating mechanism is normally locked and is only 10 released upon the operation or adjustment of the lever 22 and the depression of one of the keys of the special bank. The construction to accomplish this function will now be described.

15 The operating mechanism consists of an operating handle 69 (see Fig. 10), which has attached thereto a pinion 70, meshing with a gear 71 suitably mounted upon the machine frame. This gear 71 meshes with a 20 gear 72, which in turn meshes with a gear 73 of the same diameter, and which is secured to the shaft 38. This gear 73 has attached thereto a smaller gear 74 which meshes with a similar gear 75, the latter gear 25 being secured to a shaft 76 of the printing mechanism, hereinafter described. The above described gearing is so proportioned that two rotations of the crank handle 69 will give the shafts 38 and 76 one complete 30 rotation.

Attached to the gear 72 is a plate 77 having an abrupt locking edge 78, with which a locking shoulder 79 of a lever 80 engages. This lever 80 is secured to a rock shaft 81 35 which extends through the machine and is supported by the frames 15. This shaft 81 near its left hand end (see Fig. 5) has secured thereto a downwardly extending arm 82 which carries a wiper or by pass pawl 83, the forward edge of which contacts with a projection 84 extending from the previously described lock lever 48. When this latter lever is rocked in a clockwise direction by the operation of the pinch 40 lever 39 mounted on the adjustable lever 22, the projection 84 will pass above the forward extension of the wiper pawl 83 and the arm 82 carrying said pawl will be moved in an anticlockwise direction by a spring 85 45 secured to the extreme rearward end of the lever 80 (Fig. 10) which lever, as previously described, is secured to the right hand end of the rock shaft 81. This rocking of the shaft 81 and the arm 82 by the spring 85 50 will be limited by an arm 86, secured to shaft 81 (Fig. 4), the forward end of which will contact with a projection 87 extending from the detent 2 co-operating with the special bank of keys. This movement of the 55 rock shaft 81 is not sufficient to carry the shoulder 79 (Fig. 10) out of the path of the locking shoulder 78 of the plate 77 and consequently the machine remains locked 60 until one of the keys of the special bank is operated. Upon the depression of any one

of the keys that is in operative condition the detent 2 will be moved in a clockwise direction and thereby carry the projection 87 above a notch 88 formed near the forward edge of the arm 86 which is secured 70 to the rock shaft 81. When this projection passes above the notch 88 the spring 85 will rock the lever 80 and the shaft 81 to which it is secured so that the locking shoulder 79 75 of said lever will pass clear of the locking shoulder 78 of the plate 77.

If a wrong key has been depressed it may be released (Fig. 10) by the rocking of a centrally pivoted lever 89. This lever 89 is pivoted to the right hand side frame and 80 carries at its upper end a pin 90, while the lower end is provided with a slot 91 into which projects a pin 92 extending from a release lever 93 secured to the right hand end of the shaft 58. This shaft 58 (Fig. 4) has extending upwardly therefrom a pin 95 adjacent to the retaining bar 3 of each bank of keys. Extending laterally from each retaining bar 3 is a pin 96 with which the pin 95 engages when the release lever 93 is depressed and thereby moves the retaining bar 90 forwardly against the tension of its spring 97 so as to permit the return of the detent 2 to its normal position. This movement of the release lever 93 will, previous to the 95 forward movement of the retaining bar 3, rock the lever 89 (Fig. 10) in a clockwise direction and the pin 90 extending from the upper end of this lever will contact with the forward extension 98 of the lever 80 and 100 return lever 80 to its normal locking position. After the parts have been returned to the position above described, the pinch lever 39 and the proper key may be operated, again releasing the locking lever 80 105 so that the crank handle is then free to be operated. The gear 73 has projecting therefrom a stud 99 which, near the end of the rotation of said gear, will contact with the under side of the lock lever 80 and return 110 said lever to its normal position, as shown in Fig. 10. This return of the lock lever 80 will rock the shaft 81 so that the pawl 83 carried by the arm 82 secured to said shaft 81 (Fig. 5) will pass to the rear of the projection 84 of the lock lever 48, in which position the arm 82 will be held until the pinch lever 39 is again operated.

The slide 61 (Figs. 5 and 17) operated by the "cash" key has projecting therefrom a 120 stud 100 which, when the "cash" key is operated, passes beneath a forwardly extending arm 101 which is secured to the rock shaft 47 and prevents the rocking of said shaft by the operation of the pinch lever. The slide 62, which is operated by all of the clerks' keys, passes over an extension 102 of the lock lever 48 when any one of the clerks' keys is depressed, and thereby prevents the movement of said lever by the 125 130

pinch lever 39 after one of the clerks' keys is depressed. From this it will be seen that it is impossible to operate the pinch lever after either a "cash" or a clerk's key has been depressed, consequently it is necessary to operate the pinch lever previous to the depression of one of the special keys in order to release the operating mechanism. It is also impossible to operate a clerk's key or the "cash" key until the pinch lever 39 is released, as the extension 102 on plate 48 would be in the path of the sliding plate 62 and the arm 101 in the path of the lug 100 on plate 61.

15 *Differential mechanism.*—A differentially movable element is arranged to be controlled by either the adjustable lever 22 or the clerks' keys. It is believed that this construction is new and it is desired to 20 claim it broadly. When the lever 22 is in one of its positions in which all of the clerks' keys are locked it is necessary to control the differential element by said lever, and as previously stated the operating 25 mechanism being controlled by the lever and the depression of one of the keys of the special bank, it becomes necessary to provide the machine with a key in addition to the clerks' keys, so that when the clerks' 30 keys are locked this additional key may be operated in conjunction with pinch lever 39 for the purpose of releasing the operating mechanism. For this reason the "cash" key is provided, and is located at the bottom 35 of the bank of special keys. When the lever is in any one of its positions in which any of the clerks' keys are unlocked, these keys then control the differentially movable element and in this position of the lever the 40 "cash" key is automatically locked from operation, as previously described.

In the form shown the differential element which is controlled by the lever and the clerks' keys is one of the segments 4 and 45 this segment has mounted thereon a rocking stud 103 to one end of which is secured a plate 104 (Fig. 4) while its other end carries a similar plate 105 (Fig. 5). The plate 104 has pivoted thereto a spring operated 50 trip pawl 106, and the plate 105 has a similar pawl 107. When the segment 4 or differential element is under the control of the clerks' keys the pawl 106 will contact with the inner end of the depressed keys and rock 55 the plate 104 and stud 103 so as to disconnect a slide 108 suitably mounted upon the segment 4 from engagement with a shoulder 109 of the plate 6, as is well known and fully described in the aforementioned Cleal 60 and Reinhard patent.

The slide 40 carried by the adjustable lever 22 has at its lower end a lateral extension 110, (Figs. 7, 14 and 15), which extension is provided with a pin 111 that 65 enters into a recess in one of the horizontal

arms of a zigzag pawl 112, which pawl is pivotally mounted as at 113 to an offset 114 of a segment 115, this offset being for the purpose of connecting the adjustable lever 22 and the segment 115. When the adjustable lever is in any one of its five uppermost positions, in which position all of the clerks' keys are locked, the upper horizontal arm of the zigzag pawl 112 (Figs. 7 and 15) is in position to intercept the pawl 107 carried by the plate 105 (Fig. 5) so that when pawl 107 contacts with the upper horizontal arm of the zigzag pawl 112 the slide 108 (Fig. 4) will be disconnected from the shoulder 109 of the operating plate 6 in 80 the same manner as if the pawl 106 of the plate 104 had contacted with the inner end of one of the clerks' keys. When the lever is in any of the three lower positions, the upper horizontal arm of the zigzag pawl 85 112 will not intercept the pawl 107 carried by the plate 105, because of the fact that while the pawl is traveling in the three lower positions it will be held depressed by a roller 116 mounted on said pawl engaging 90 with the cam portion 117 of a plate 118, which is supported at its lower end by the rock shaft 58 and at its upper end by a stud 119, projecting from the left hand side frame. As the "cash" key is used only in 95 releasing the operating mechanism when the lever is in any one of its five uppermost positions, and as said key does not in any instance control the differential element, it is necessary to provide mechanism to prevent 100 the pawl 106 from contacting with the inner end of the depressed key, and this is accomplished by attaching a cam plate 120 to the detent 2, (Fig. 4) so that a roller 121 carried by the said pawl will engage the 105 said plate 120 and rock the pawl and hold it in its rocked position while traveling beneath the "cash" key, so that the latter when depressed will not intercept said pawl. 110 The segment 115 which is connected to the adjustable lever 22 has projecting therefrom (Fig. 5) a pin which is similar to the pins 16 projecting from the segments 4, and this pin plays in the slot 17 of one of the arms 18, which arm is connected to the shaft 20. The object of this is to set a type carrier for recording the special transactions "charge," "received on account" and "paid out." In the six upper positions of the lever the type carrier controlled by this lever will be positioned to print a character representing "cash." The differential segment 4 which is controlled by both the clerks' keys and the adjustable lever 22 positions the type carrier, through pin 16 and slot 17 of arm 18 and intervening connections, for recording the characters designating the different clerks. The segment 115 meshes with one of the intermediate gears 115 8 which in turn meshes with a similar gear 118

12 attached to an indicator 13 and positions the said indicator 13 in the same manner as do the differentially movable segments 4.

In some of the claims the term "digit carrier" has been used and this term is intended to cover any element having digits thereon, for example a registering wheel, type carrier or indicator.

Check issuing mechanism.—The mechanism about to be described accomplishes one of the principal objects of the invention, viz: to provide a flexible or adjustable control of the check issuing mechanism.

Heretofore machines have been constructed so that when certain keys are depressed or the adjustable lever moved to certain positions, the check issuing mechanism will be rendered operative. The great objection to such mechanism has been that after they are installed the proprietor often desires to render the check issuing mechanism operative when other transactions take place than those for which the machine was originally constructed, but this has been, as far as known, impossible without reconstructing the machine. It is a principal object of this invention to provide mechanism which may be adjusted at the will of the proprietor or other authorized persons so that upon the recording of any transaction the check issuing mechanism may be enabled or disabled. This is accomplished by the following described mechanism. The segment 115, which is secured to the adjustable lever 22, meshes with a gear 122 (Fig. 5) which is secured to a rock shaft 123. This shaft has secured thereto a disk 124 (Fig. 6), which disk is provided with adjustable pins 125. These pins are screwed into a disk 124 and may be detached at will through a suitable opening formed in the back of the cabinet (not shown), and which opening is normally covered and locked so that access to the pins 125 can be had only by the proprietor or some authorized person. When it is desired to issue a check upon all the transactions entered in the machine, the disk is provided with as many pins as there are positions of the lever and in this manner one of these pins, no matter what position the lever is in, will contact with a link 126 as at 127 (Figs. 5 and 16) and hold an extension 128, formed at the lower end of said link, beneath a stud or pin 129, against the tension of a spring 130, the ends of the latter being secured to the link 126 and to one of the frames 15. The pin 129 projects from an arm 131 suitably secured to a shaft 132. This shaft is divided and the two parts thereof are connected by a yoke 133 (Fig. 4) so as to permit the passage of a drawer release plunger 134, hereinafter described.

To prevent the pins 125 from contacting with the projection 127 of the link 126, while the disk 124 is being rotated by the

movement of the adjustable lever 22, a pin 125^a is provided which extends from the locking arm 48 into a slot 126^a formed in the link 126 (Figs. 2 and 16). It will be recalled that in order to move the lever 22, it is necessary to operate the pinch lever 39, by which movement the locking lever 48 will be moved in a clockwise direction (Fig. 2). By this movement of the lever 48, the pin 125^a will contact with the inclined edge 75 of the slot 126^a and thereby hold the projection 127 of the link 126 away from the pin 125 while the adjustable lever is being positioned.

Shaft 132 extends to the right hand side 80 of the machine (Fig. 8) and has extending downwardly therefrom an arm 135, which arm is connected by a link 136 to an arm 137 secured to a stud shaft 138 suitably mounted in the printer frame. This stub shaft is 85 provided with an eccentric portion 139 which carries a feed roller 140 of the check issuing mechanism. This roller 140 is provided with a gear 141 which meshes with a similar gear 142. This latter gear meshes 90 with another gear 143 of the same diameter and this gear in turn meshes with a gear 144 secured to the previously described shaft 76. Also secured to this shaft 76 is a feed roller 95 145 which coacts with a similar feed roller 146 to which is secured a gear 147 that meshes with the gear 144. The feed roller 146 and gear 147 are mounted upon an eccentric 148 on a stub shaft 149, which is suitably mounted in the printer frame. Secured to the stub shaft 149 is an arm 150 which is connected to a centrally pivoted lever 151 by a link 152. The lower end of the centrally pivoted lever 151 is connected to the arm 137 which is secured to the stub shaft 138 carrying the feed roller 140. The feed roller 140 coacts with a similar feed roller 153 to which is secured the gear 142 and these feed rollers 140 and 153 and the feed rollers 145 and 146 are normally out of 100 operative relation so that no check will be issued if the machine should be operated with the rollers in this position. Upon the operation of the machine, with one of the pins 125 contacting with the portion 123 of the link 126, the said link will be elevated upon the very beginning of the operation of the machine by a cam groove 154 formed in the disk 50 and into which plays a roller 155 105 projecting from the upper end of the link 126. This elevation of the link 126, will, through the contact of the projection 128 on the lower end of said link with the pin 129, rock the shaft 132 (in a counter clockwise direction in Fig. 5). This movement of the shaft 132 (in a clockwise direction in Fig. 8) 110 will rock the shaft 138 through the link 136 and arm 137 in a similar direction, which movement of the shaft 138 will, through the eccentric portion 139 of said shaft, carry the 115 120 125 130 135 140 145 150 155 160

feed roller 140 into coöperative relation with the feed roller 153. This movement of the shaft 132 will also rock the lever 151 in a clockwise direction, which lever will, 5 through the link 152, rock the shaft 149 so that the eccentric portion 148 of said shaft will carry the feed roller 146 into operative relation with the feed roller 145. A disk 10 suitably secured to the shaft 76 has an annular projection 1561 formed with an opening 157. As this adjusting movement of the various feed rollers occurs at the very beginning of the operation of the machine, a roller 156 will pass through this opening 157 and hold said rollers in their adjusted 15 positions until the end of the operation of the machine, near which the various parts will be returned to their normal positions, shown in Fig. 8, by a spring 158, the ends of 20 which are secured to the arm 137 and to the printer frame.

With the rollers in operative position, the check strip 159 will be fed by said rollers through a suitable opening in a stationary 25 knife 160 and over a platen 161 to have an impression taken thereon from the type carriers 21. This platen is carried in a frame 162, to which is connected the forward end 30 of a lever 163, which at its rear end is pivoted as at 164 to the printer frame. Projecting from about the center of this lever 163 is a roller 165 which plays in a cam groove 166 formed in a disk carried by the inner end of the lower feed roller 140. The 35 shape of the cam groove 166 is such that frame 162 carrying the platen 161 will be given two movements of different extents at each operation of the machine. A knife 167^a is carried by the frame 162 and this 40 knife is arranged to coact with the stationary knife to sever the strip 159 into checks.

If, upon some transactions, it is not desired to issue a check the pins 125, which co-operate with the link 126 when these particular 45 transaction totalizers are in operative relation with the actuators 11 will be detached from the disk 124, so that the lower end of the link 126 will move rearwardly with the projection 128 out of operative 50 relation with the pin 129. Upon the operation of the machine with the link in this condition the shaft 132 will not be rocked, and consequently the feed rollers will not be brought into operative relation with each other, so that no check will be issued upon 55 this operation. In other words the eccentrics 139 and 148 are not rotated to move the rollers 140 and 146 into contact with their respective opposing rollers 153 and 145. 60 However, the teeth on the gears carried by these pairs of rollers are long enough to remain in engagement in this inoperative position so that both of the rollers 140 and 146 are rotated, but as the center about which 65 roller 140 rotates is lower at this time, the

cam groove 166, while it operates the platen 161 and the movable knife 167^a to the same extent as in the operative position, because of the lower center of rotation mentioned does not raise either the platen or the knife 70 high enough for them to perform their functions.

With the above described construction it will be seen that the check issuing mechanism may be enabled or disabled at will in 75 connection with transactions of any class within the range of the machine.

In machines having a plurality of totalizers or accounting devices for keeping separately the transactions of the different 80 clerks, it is also desirable to keep separately a detail record of the various amounts that go to make up the totals of each of the clerks' totalizers and a novel form of mechanism for accomplishing this function is 85 provided. This mechanism comprises duplicate impression means and a device for perforating the check strip between the impressions so that a part of the check strip may be retained by the clerk, while the rest 90 of the said strip may be given to the customer as a receipt for the purchase.

As previously stated, the cam groove 166 imparts two movements of different extents to the platen carrying frame 162, the purpose of which is to enable the platen 161 to take the first impression from the type without severing the check. The platen 161 has four sides and each side is provided with a rubber impression block 167. This platen 100 is arranged to be rotated and two of the impression blocks 167 are located at heights from the center of the platen 161 differing from the heights of the remaining two impression blocks 167. Attached to this platen 105 161 is a ratchet wheel 168 which, when said platen is elevated and lowered, is arranged to engage with a pawl 169 pivotally mounted upon the printer frame. Upon the first upward movement of the platen frame 162 one 110 of the impression blocks 167 which is removed farthest from the center of the platen will contact with the type carriers 21 and take an impression upon the check strip, which has previously been fed over the impression block. This movement imparted to the platen carrying frame 162 is not sufficient to permit the knife 167^a carried by the frame 162 to sever the check. Upon the lowering of the platen frame after the taking 115 of this first impression, one of the teeth of the ratchet wheel 168 will engage with the pawl 169 and cause said pawl to rotate the platen so as to bring one of the rubber impression blocks 167, that is nearest to the point of rotation of said platen, into position to take an impression from the type carriers when the platen carrying frame 162 is elevated the second time. Upon the elevation of the platen 167 while in this position 120 125 130

tion the knife 167^a will sever the check strip 159, and upon the return of the platen carrying frame the said platen 161 will again be partially rotated bringing the lower block, (in Fig. 8) into position so that upon the next elevation of the platen, this block will take an impression from the type carriers 21.

A chute 201^a is formed in a casing 201 (Fig. 2), which surrounds the printing mechanism, and into this chute the free end 10 of the issued check passes, so that when said check is severed, the operator may grasp the free end thereof and remove the check from the machine.

An inverted L-shaped plate 170 (see Fig. 15 9) is carried by the frame 162, which plate acts as a support for the outer end of the platen 161. The feed rollers are so constructed that at the time the platen 161 is 20 elevated to take an impression from the check strip, the said strip will not be fed but will be fed before and between the taking of impressions. A plate 171 having a serrated edge is embodied in the feed roller 153 and is located in such a position relative to the 25 feeding of the check that the check will be perforated by the plate 171 between the impressions taken thereon. It will be seen that in the construction shown the check issued 30 by the machine is perforated at the previous operation of the machine, but it is to be understood the invention is not limited to such a timing and manner of perforating the check. One feed roller of each pair may 35 be equipped with suitable electro-plates for the purpose of printing any suitable advertisements upon the front and the back of the check. An ink roller 172 is shown for inking the electro-plates of the lower pair of 40 feed rollers, and this roller is supported by a chute 173 through which the check strip 159 passes, it being understood that a similar ink roller, not shown, is also provided for the upper pair of feed rollers.

Autographic detail strip mechanism.—It 45 is often desirable in accounting machines having recording mechanism to employ a wide record strip so that a memorandum may be written opposite the recorded transaction, but in a number of machines now 50 upon the market the record strip is fed above the type carriers and the record is made on the under side of said strip, in which case the strip is inaccessible to have 55 memoranda made thereon. It is one of the objects of this invention to provide mechanism for rendering such a strip accessible, and this mechanism will now be described.

A frame 174 (Fig. 2) is rotatably mounted 60 as at 175 to a sliding plate 176 (Fig. 12). The frame 174 carries a supply roll 177, from which a record strip 178 is led over a platen 179 mounted in the frame 174 and thence to a storage roll 180 also mounted in 65 said frame. A pinion 181 is mounted on the

frame 174 and meshes with a rack 182 (Fig. 12), this rack being suitably guided in the plate 176. Projecting from this rack plate 182 is a roller 183 which enters an elongated slot 184 formed in the forward end of an arm 185, which is pivoted to the printer frame as at 186. Extending downwardly from the arm 185 is a pitman 187, which is forked at its lower end and straddles a collar mounted upon the shaft 76, and near its forked end this pitman is provided with a roller 188 which projects into a cam groove 189 formed in a disk 190 secured to the shaft 76.

The plate 176 is slidably mounted within guides 191 which are suitably attached to the printer frame (Fig. 13), and has projecting therefrom a roller 192 which projects through a suitable opening in the printer frame and into an elongated slot 193 formed in the forward end of an arm 194, which has the same pivotal point as the arm 186 but is on the opposite side of the printer frame. This arm 194 has attached thereto one end of a pitman 195, the lower end of which is forked and straddles a collar secured to the shaft 76. A roller 196 extending from the lower end of the pitman 195 projects into a cam groove 198 formed in a disk 199 which is secured to the aforesaid shaft 76. The platen 179 stands normally below an opening 200 in the casing 201 for the printing mechanism, through which opening any suitable memoranda may be made upon the record strip 198. The shape 100 of the cam groove 189 in the disk 190 is such that shortly after the beginning of the operation of the machine, the rack plate 182 will be elevated, by which movement the frame 174 carrying the platen 179 will be 105 rotated. This frame 174 will be rotated far enough by the rack 182 so as to bring the platen 179 directly above the characters of the type carriers 21 that are in printing position. During this rotation of the platen 110 carrying frame 174, the plate 176 in which said frame is rotatably mounted, will be gradually lowered by its cam disk 199 and after the platen 179 has been positioned relative to the type carriers 21, the cam disk 199 115 will further lower the platen carrying frame 174, so as to take an impression upon the record strip in alignment with the written memoranda made thereon, after which the platen carrying frame will be restored to its 120 normal position, as shown in Fig. 2, by the cam disks 190 and 199.

Slidably mounted upon the frame 174, by slot and pin connections 202 and 203 respectively, is a plate 204, which plate carries a pawl 205 that is held in engagement with the teeth of a ratchet wheel 206 by a spring 207. Projecting from the upper end of this plate is a roller 208, which extends through an opening 209 in the frame 174 and into 130

the upper end of a cam slot 210 formed in a plate 211, which is securely attached to the printer frame. The shape of the cam slot 210 is such that as the platen carrying frame 174 is rotated, the plate 204 will be moved longitudinally upon guide pins 203 so that the pawl 205 will engage one of the teeth of the ratchet wheel 206 and rotates said ratchet and the storage roller 180, to which it is secured, as the platen frame 174 is rotated. A spring pressed retaining pawl 212 pivotally mounted upon the frame 174 engages the teeth of the ratchet 206 and thereby holds the storage roll 180 in its advanced position.

Upon the printer casing 201 below the opening 200 therein is mounted a glass plate 213 through which may be seen a number of items previously recorded upon the record strip 178.

Inking ribbon reversing mechanism.—A ribbon is used to take impressions from the type carriers 21 and a novel form of mechanism for automatically reversing the feed 25 of the ribbon is employed, which mechanism will now be described.

The ribbon 214 is fed from a roller 215 to a roller 216 and after the supply has been exhausted from the first mentioned roller, 30 the feed of the ribbon is automatically reversed so as to return it to roller 215. The ribbon 214 passes from the roller 215 around the type carriers 21, it being guided by pins 217 supported by the printer frame, and 35 thence to the roller 216. A bell crank lever 218 is mounted upon a stud 219, which supports the roller 215. The downwardly extending arm of the bell crank 218 is provided with a stud 220 (Figs. 2 and 10), 40 which enters a recess 221 formed in the lower end of a lever 222 which is centrally pivoted to one of the side frames of the machine. The upper end of the lever 222 carries a roller 223, which plays in a cam groove 224 formed in a plate 225, which is secured to the intermediate gear 71. This gear is given a half rotation at each operation of the machine and consequently the cam groove 224 is formed of two portions which 45 are identical, so that the lever 222 will be reciprocated an invariable extent at each operation of the machine. As the lever 222 is reciprocated, the bell crank 218 will first be rocked in a clockwise direction and then 50 returned to normal position. The free end of the horizontal arm of the bell crank 218 is connected to the lower end of a slide 226, the upper end of which is pivoted to an arm 227, which in turn is pivoted to a stud 228 55 carrying the upper ink ribbon roller 216. The slide 226 has pivoted thereto pawls 229 and 230, which are arranged to coöperate respectively with ratchet wheels 231 and 232, which are connected to rollers 215 and 216. 60 Mounted upon the slide 226, and upon the

same pivotal points as the pawls 229 and 230, are rack plates 233 and 234 respectively. These rack plates are connected by a segmental pinion 235, which is also pivoted upon the slide 226. Pivoted upon an arm 70 236 of slide 226 is a rack plate 227, which plate meshes with the segmental pinion 235. The pinion 235 and plate 237 have extensions 238 and 239 respectively to which are connected the ends of a spring 240.

By referring to Fig. 2, it will be seen that if the bell crank 218, which is pivoted upon the stud 219 of the lower ink roller 215, is rocked in a clockwise direction, the slide 226 will be lowered, by which movement the pawl 229, which is in engagement with the ratchet 231, will rotate said ratchet and the roller 215 in a clockwise direction, thereby feeding the ink ribbon 214 from the roller 216 on to the roller 215. Extensions 240 and 241 of the segmental plates 233 and 234, respectively, have springs 242 interposed between said extensions and the pawls 229 and 230, and thereby tend normally to force the said pawls toward the ratchets 231 and 232. The feed pawls and the companion segmental plates with which they are pivotally mounted to the slide 226 have mill cuts as at 243^a (Fig. 3) which limits the movement of the pawls relative to the segmental plate with which it coöperates, when said pawls are out of engagement with the ratchet wheels. Arms 243 and 244 are mounted upon the studs 219 and 228 respectively, and are connected by a coil spring 245. The free ends of these arms 243 and 244 coat respectively with the rolls of ink ribbon 216 and 215. These arms 243 and 244 have projections 246 and 247 respectively. As the ribbon is fed from the roller 216 on to the roller 215, the arm 244 will be gradually rocked in a clockwise direction, as the diameter of the roller 215 increases, while the arm 243 will be rocked in a similar direction by the spring 245, as the diameter of the roller 216 decreases. When the ribbon from the roller 216 is nearly exhausted the projection 246 of the arm 243 will pass above an offset 248 of the segmental plate 237, as said segmental plate is carried to its lowermost position upon the rocking of the bell crank 218 by the lever 222. Upon the return movement of the slide 226 and segment plate 237, the offset 248 will contact with the under side of the projection 246 of the 100 arm 243 and thereby rock said segmental plate 237. This rocking of the plate 237 will rock the pinion 235 in a clockwise direction until the line between the extensions 238 and 239 of the pinion 235 and the plate 105 237 respectively, to which the ends of the spring 240^a are attached passes below the line joining the pivotal points of the pinion 235 and the plate 237, in which position they will be held by the said spring 240. 110 115 120 125 130

This rocking of the pinion 235 will rock the plates 233 and 234 and by the mill cuts 243 (Fig. 3), will rock the pawls 229 and 230, the former out of engagement with its ratchet 231 and the latter of said pawls into engagement with its ratchet 232, so that upon succeeding operations of the machine, the pawl 230 will actuate the ratchet 232 attached to the upper 5 roll 216, and thereby feed the ribbon 214 on to said roll. With this construction it will be seen that a very novel and efficient form of positive reversing mechanism for the feed of the inking ribbon is provided, and one 10 which does not require any tension to be given to the ribbon to effect the reversal.

Drawer releasing mechanism.—A great many machines having a plurality of totalizers for keeping separately the receipts of 20 the different clerks are also provided with a corresponding number of cash receptacles. With machines constructed as described in this application, the clerks' keys are locked when the clerks' totalizers are brought into 25 coöperative relation with the actuators, and when other totalizers are brought into such relation with the actuators, the clerks' keys are unlocked. To provide a multiple drawer attachment to the construction before 30 described, it becomes necessary to provide releasing mechanism for the cash receptacles which is under the control of the adjustable lever and the clerks' keys, to accomplish the function mentioned.

35 The differential element or segment 4 which is controlled by the manipulative device or adjustable lever 22 and the bank of special keys meshes with a gear 250 (Figs. 4 and 6), which gear is secured to one end of 40 a sleeve 251 loosely mounted upon the shaft 123. This sleeve at its other end is provided with a beveled gear 252 which meshes with a similar beveled gear 253 splined to the releasing shaft 134 for the cash receptacles. This shaft 134 has fingers 254 projecting therefrom, which fingers are arranged to be brought into coöperative relation with latches 255 of cash receptacles 45 256. After the proper finger 254 on the shaft 134 has been positioned, the shaft will be elevated by a cam 257 secured to the main shaft 38. This cam engages with a roller 258 secured to the upper end of a link 259, the lower end of this link being bent laterally to straddle the upper end of shaft 134, and engage with the under side of a pin 260 projecting from the upper end of said shaft 134. This method of releasing or exposing 50 the cash receptacle 256 by the elevation of the finger shaft 134 is well known and no further description need be given. The cash receptacles when released are moved to accessible positions by springs (not shown) located in the rear of the receptacles.

55 While the form of mechanism herein

shown and described is admirably adapted to fulfil the objects primarily stated, it is to be understood that it is not intended to confine the invention to the one form of embodiment herein shown and described, as 70 it is susceptible of embodiment in various forms, all coming within the scope of the claims which follow.

What is claimed is:—

1. In an accounting machine, the combination with an operating mechanism for entering different classes of transactions therein, of means for determining the class of transaction to be entered in the accounting machine by said operating mechanism, 75 a check issuing mechanism, and devices adjustable at will and coöperating with the determining means for controlling the check issuing mechanism.

2. In an accounting machine, the combination with an operating mechanism for entering different classes of transaction therein, of means for determining the class of transaction to be entered in the accounting machine by said operating mechanism, 80 a normally inoperative check issuing mechanism, and devices adjustable at will and coöperating with the determining means for rendering the check issuing mechanism operative.

3. In an accounting machine, the combination with an operating mechanism for entering different classes of transactions therein, of means for determining the class of transaction to be entered in the accounting machine by said operating mechanism, 85 a check issuing mechanism, and detachable devices coöperating with the determining means for controlling the check issuing mechanism.

4. In an accounting machine, the combination with type carriers for recording different classes of transactions upon a record strip and a check strip, of normally inoperative mechanism for issuing and severing 110 the latter strip into checks, means for determining the class of transactions to be recorded upon the record and check strips, and devices adjustable at will and coöperating with the determining means for rendering the check issuing and severing mechanism operative.

5. In an accountable machine, the combination with type carriers for recording different classes of transactions upon a record 115 strip and a check strip, of mechanism for issuing and severing the latter strip into checks, means for determining the class of transaction to be recorded upon the record and check strips, and devices adjustable at will and coöperating with the determining means for enabling and disabling the check issuing and severing mechanism.

6. In an accounting machine, the combination with type carriers for recording dif- 120

- ferent classes of transactions upon a record strip and a check strip, mechanism for issuing and severing the latter strip into checks, means for determining the class of transaction to be recorded upon the record and check strips, and means including detachable devices coöperating with the determining means for enabling and disabling the check issuing and severing mechanism.
6. In an accounting machine, the combination with type carriers for recording different classes of transactions upon a record strip and a check strip, of normally inoperative rollers for feeding the latter strip, means for determining the class of transaction to be recorded upon the record and check strip, and devices adjustable at will and coöperating with the determining means for rendering the feed rollers operative.
10. 7. In an accounting machine, the combination with type carriers for recording different classes of transactions upon a record strip and a check strip, of normally inoperative rollers for feeding the latter strip, means for determining the class of transaction to be recorded upon the record and check strip, and devices adjustable at will and coöperating with the determining means for rendering the feed rollers operative.
15. 8. In an accounting machine, the combination with type carriers for recording different classes of transactions upon a record strip and a check strip, of means for determining the class of transaction to be recorded, rollers for feeding the check strip, and adjustable devices coöperating with the determining means for enabling and disabling the feed rollers.
20. 9. In an accounting machine, the combination with type carriers for recording different classes and amounts of transactions upon a check strip, of an adjustable element for positioning the type carrier for recording the classes of transactions, normally inoperative rollers for feeding the check strip, and mechanism, including detachable devices, connected to the adjustable element for rendering the feed rollers operative.
25. 10. In an accounting machine, the combination with type carriers for recording different classes and amounts of transactions upon a check strip, of an adjustable element for positioning the type carrier for recording the classes of transactions, normally inoperative rollers for feeding the check strip, mechanism, including detachable devices, connected to the adjustable element for rendering the feed rollers operative, and mechanism by one of the feed rollers when in operative condition for severing said strip into checks.
30. 11. In an accounting machine, the combination with a type carrier, of an impression mechanism having contact surfaces of different heights for taking a plurality of impressions upon a check strip from the type carrier, means for imparting to said mechanism a variable movement, and means moving with the impression mechanism for severing the check strip when the lowest surface of the impression mechanism is brought into contact with the type carrier.
35. 12. In an accounting machine, the combination with a type carrier, of an impression mechanism having contact surfaces of different heights for taking a plurality of impressions upon a check strip from the type carrier, means for imparting to said mechanism a variable movement, devices actuated during the movement of the impression mechanism for adjusting said mechanism for the purpose of bringing the different contact surfaces thereof into operative relation with the type carrier, and means for severing the check strip when the lowest surface of the impression mechanism is brought into contact with the type carrier.
40. 13. In an accounting machine, the combination with a type carrier, of a rotating platen having contact surfaces of different heights for taking a plurality of impressions upon a check strip from the type carrier, means for imparting to said platen a variable movement, devices actuated during the movement of the platen for rotating said platen for the purpose of bringing the different contact surfaces thereof into operative relation with the type carrier, and means for severing the check strip when the lowest surface of the platen is brought into contact with the type carrier.
45. 14. In an accounting machine, the combination with a type carrier, of a rotating platen having contact surfaces of different heights for taking a plurality of impressions upon a check strip from the type carrier, a frame carrying said platen, means for imparting to said platen a variable movement, devices actuated by the movement of said frame for rotating the platen for the purpose of bringing the different contact surfaces thereof into operative relation with the type carrier, and a knife carried by the frame for severing the check strip when the lowest surface of the platen is brought into contact with the type carrier.
50. 15. In an accounting machine, the combination with a type carrier, of a rotating platen having contact surfaces of different heights for taking duplicate impressions upon a check strip from the type carrier, a frame carrying said platen, means for imparting to the frame a variable movement, devices for rotating the platen for the purpose of bringing the different contact surfaces thereof into operative relation with the type carrier, rollers for feeding the check strip, a device carried by one of the feed rollers for perforating said strip between the duplicate impressions, and a knife carried by the platen frame for severing the check strip when the lowest surface of the platen is brought into contact with the type carrier.
55. 16. In an accounting machine, the combination with a type carrier, of a movable frame carrying a record strip, the latter normally being in position to have a written entry made thereon, means for moving the frame for the purpose of bringing the

- record strip and type carrier into coöperative relation, and means for then imparting a further movement to the frame thereby taking an impression from the type carrier upon the record strip in juxtaposition to the written entry made thereon. 5
17. In an accounting machine, the combination with a type carrier, of a movable frame carrying a record strip, the latter normally being in position to have a written entry made thereon, means for moving the frame for the purpose of bringing the written entry on the record strip in alinement with the type carrier, means for imparting a further movement to the frame whereby an impression is made from the type carrier upon the record strip in juxtaposition to the written entry made thereon, and means for feeding the record strip during the movement of the frame. 10
18. In an accounting machine, the combination with a type carrier, of a platen, a frame carrying said platen and a record strip, the platen normally being in position to have a written record made on the strip, means for adjusting the frame so as to bring the platen into coöperative relation with the type carrier, means for taking an impression upon the record strip after the platen has been brought into coöperative relation with the type carrier, and means carried by the frame for feeding the record strip during the adjustment of said frame. 25
19. In an accounting machine, the combination with an operating mechanism, of a spring operated means normally locking said mechanism, a plurality of accounting devices, actuators therefor, an adjustable lever for moving said accounting devices into coöperative relation with the actuators, a series of keys, a lug normally obstructing the movement of the locking mechanism, means actuated by the adjustable lever for removing the lug from obstructing position and thereby partially releasing the locking mechanism, and means under the control of the keys for completely releasing the locking mechanism after the latter has been partially released, the said key controlled means limiting the movement of the locking means when released by the adjustable lever. 35
20. In an accounting machine, the combination with an operating mechanism, of a spring operated means normally locking said mechanism, a plurality of accounting devices, actuators therefor, an adjustable lever for moving said accounting devices into coöperative relation with the actuators, a series of keys, a lug normally obstructing the movement of the locking mechanism, means under the control of the adjustable lever for removing the lug from obstructing position and thereby partially releasing the locking mechanism, means under the control of the keys for completely releasing the locking 40
- 55
- 60
- 65
- mechanism after the latter has been partially released, the said key controlled means limiting the movement of the locking means when released by the adjustable lever, and means preventing adjustment of the lever after a key has been depressed. 70
21. In a machine of the class described, the combination with a plurality of accounting devices, of actuators common thereto, means for bringing any one of the accounting devices and the actuators into coöperative relation, an operating mechanism for the actuators, means normally locking the operating mechanism, a series of keys controlling the operating mechanism locking means, and locking means for the keys constructed so that when certain ones of the accounting devices are in coöperative relation with the actuators one of said keys will be free to be operated, and when other accounting devices are in coöperative relation with the actuators said one key will be locked and the other keys of the series will be unlocked. 75
22. In a machine of the class described, the combination with a plurality of accounting devices for keeping separately transactions of clerks and special transactions, of actuators common thereto, means for bringing any one of the accounting devices and the actuators into coöperative relation, an operating mechanism for the actuators, means normally locking the operating mechanism, a series of keys, comprising clerks' keys and a special key, for controlling the locking means for the operating mechanism, and locking means for the keys constructed so that when any one of the clerks' accounting devices is in coöperative relation with the actuators the clerks' keys will be locked and the special key unlocked, and when any one of the special accounting devices is in coöperative relation with the actuators the clerks' keys will be unlocked and the special key locked. 80
23. In a machine of the class described, the combination with a plurality of clerks' and special accounting devices, of actuators common thereto, an adjustable lever for bringing any one of the accounting devices and the actuators into coöperative relation, an operating mechanism for the actuators, means normally locking said operating mechanism, a series of clerks' and special keys for controlling the locking means for the operating mechanism, and locking means for the keys constructed so that when one of the clerks' accounting devices is in coöperative relation with the actuators certain of the clerks' keys only will be unlocked, and when any other of the clerks' accounting devices is in coöperative relation with the actuators the special key only will be unlocked, and when the special accounting devices are brought into coöperative relation 85

- with the actuators all of the clerks' keys will be unlocked.
24. In an accounting machine, the combination with an operating mechanism, of an element differentially moved thereby, a plurality of independent means and mechanically operative connections between the independent means and the differentially movable element for controlling similar extents of movement in the same direction of the differentially movable element and a digit carrier connected to said element.
25. In an accounting machine, the combination with an operating mechanism of an element differentially moved thereby, a plurality of independent means and mechanically operative connections between the independent means and the differentially movable element for controlling similar extents of movement of the differentially movable element, a digit carrier connected to said element, and means for disabling the rest of the controlling means when one of said means is in operative condition.
26. In an accounting machine, the combination with an operating mechanism therefor, of an element differentially positioned by said operating mechanism, an adjustable lever for determining the extent of movement of the differential element, a series of keys for also determining the extent of movement of said element, and means for disabling either the determining lever or the keys when the other is in operative condition.
27. In an accounting machine, the combination with an operating mechanism, of an element differentially moved thereby, a plurality of independent means and mechanically operative connections between the independent means and the differentially movable element for controlling the similar differentially movable element in similar extents of movement, said connections being so constructed that but one independent means controls the differentially movable element upon any operation of the machine, and a digit carrier connected to said element.
28. In an accounting machine, the combination with an operating mechanism, of an element differentially set by said operating mechanism, a digit carrier connected to said element, an adjustable lever for determining the extent of movement of the differential element, a series of keys for also determining the extent of movement of said element, and means for disabling the keys when the lever is in position for determining the extent of movement of the differential element.
29. In an accounting machine, the combination with an operating mechanism for entering transactions therein, of a plurality of cash receptacles, and a plurality of means, either of which may be used for determining the opening of any desired receptacle upon the operation of the operating mechanism.
30. In an accounting machine, the combination with an operating mechanism therefor, of a plurality of cash receptacles, an element differentially positioned by said mechanism and constructed to expose any one of the cash receptacles, an adjustable lever for determining the cash receptacle to be exposed by the differential element, a series of keys for also determining the cash receptacle to be exposed by the differential element, and means for disabling the keys when the lever is in position for determining the cash receptacle to be exposed.
31. In an accounting machine, the combination with an operating mechanism, of an element differentially moved thereby and an adjustable manipulative device and connections constructed to control the differentially movable element while said device is in certain positions and to relinquish the control thereof while in other positions.
32. In an accounting machine, the combination with an operating mechanism, of an element differentially moved thereby, an adjustable manipulative device and connections constructed to control the differentially movable element while said device is in certain positions and to relinquish the control thereof while in other positions, and a series of keys for controlling the differentially movable element when the adjustable device is in any of the last mentioned positions.
33. In an accounting machine, the combination with an operating mechanism, of an element differentially moved thereby, an adjustable manipulative device and connections constructed to control the differentially movable element while said device is in certain positions and to relinquish the control thereof while in other positions, a series of keys for controlling the differentially movable element when the adjustable device is in any of the last mentioned positions, and means controlled by the manipulative device when in the first mentioned positions for preventing operation of the keys.
34. In an accounting machine, the combination with a differentially adjustable manipulative device, of a series of keys, and means controlled by said manipulative device while in a plurality of positions for preventing the operation of all but one of said keys and while in other positions for preventing the operation of the previously unlocked key and permitting the operation of the other keys.
35. In an accounting machine, the combination with a differentially adjustable manipulative device, of a series of keys; and means controlled by said manipulative de-

vice when in one position for locking all but one of said keys, and when in a second position unlocking a portion of the previously locked keys and locking the previously unlocked key, and when in a third position unlocking all of the first mentioned locked keys and locking the key that is unlocked when the manipulative device is in its first mentioned position.

36. In an accounting machine, the combination with an operating mechanism for entering different classes of transactions therein, of an adjustable means for determining the class of transaction to be entered in the accounting machine by said operating mechanism, removable pins a check issuing mechanism, and an element rotated by operations of the aforesaid adjustable means and carrying the removable pins for controlling 20 said check issuing mechanism.

37. In an accounting machine, the combination with an operating mechanism for entering different classes of transactions therein, of manipulative means for determining the classification of items entered in the accounting machine by said operating mechanism, a check issuing mechanism and an element operated by the aforesaid manipulative means and carrying removable 30 elements for controlling the check issuing mechanism.

38. In an accounting machine, the combination with a plurality of totalizers, of actuators common thereto, means for establishing coöperative relation between any one of the totalizers and the actuators, a check issuing mechanism, and devices operated by the said establishing means and adjustable at will for controlling said check issuing 40 mechanism.

39. In an accounting machine, the combination with a plurality of accounting devices, of a common operating mechanism therefor, means for establishing coöperative relation 45 between any one of the accounting devices and the operating mechanism, a check issuing mechanism, and devices operated by the aforesaid establishing means and adjustable at will for controlling said check issuing 50 mechanism.

40. In an accounting machine, the combination with a plurality of registering devices, of a common operating mechanism therefor, manipulative means for establishing 55 coöperative relation between any desired one of the registering devices and said operating mechanism, a check issuing mechanism, and detachable devices coöperating with the aforesaid manipulative means for 60 controlling said check issuing mechanism.

41. In an accounting machine, the combination with a plurality of record retaining devices, of a common operating mechanism therefor, manipulative means for establishing 65 coöperative relation between any de-

sired one of the record retaining devices and said operating mechanism, a check issuing mechanism, and an element moved by operations of said manipulative means and carrying removable pins for controlling the 70 check issuing mechanism.

42. In an accounting machine, the combination with a plurality of accounting devices, of a common operating mechanism therefor, manipulative means for establishing coöperative relation between any desired accounting device and the operating mechanism, a check issuing mechanism, and an element rotated by the aforesaid manipulative means and carrying removable 75 pins for controlling the check issuing mechanism.

43. In an accounting machine the combination with a movable frame, of a plurality of accounting devices carried thereby, a common operating mechanism for said accounting devices, means for selectively establishing coöperative relation between any desired accounting device and the operating mechanism, a check issuing mechanism, and a device positioned by the aforesaid selecting means and comprising detachable elements for controlling said check issuing mechanism.

44. In an accounting machine, the combination with a rotatable frame, of a plurality of totalizers carried thereby, actuators for said totalizers, a lever for rotating said frame to bring any totalizer into operative relation with the actuators, a normally inoperative check issuing mechanism, and an element rotated by the aforesaid manipulative device and carrying removable pins for rendering the check issuing mechanism 95 operative.

45. In an accounting machine, the combination with a plurality of record retaining devices, of a common operating mechanism therefor, means for establishing operative relation between any record retaining device and said operating mechanism, a normally inoperative check issuing mechanism, an element positioned by said establishing means and carrying detachable elements for rendering the check issuing mechanism 100 operative when certain record retaining devices are in operative relation to the operating mechanism.

46. In an accounting machine, the combination with an operating mechanism for entering different classes of transactions therein, of means for determining the class of transactions to be entered in the accounting machine by said operating mechanism, type carriers, means coöperating with the type 110 carriers to take impressions therefrom, and an element operated by said determining means and carrying detachable devices for controlling said impression taking means.

47. In an accounting machine, the combi- 115

nation with an operating mechanism for entering different classes of transactions therein, of manipulative means for determining the class of transactions to be entered in the accounting machine by said operating mechanism, type carriers, an impression taking means coöperating with said type carriers, and a platen operated by the aforesaid manipulative means and carrying devices removable to disable said impression taking means when certain classes of items are entered in the accounting machine.

48. In an accounting machine, the combination with type carriers for recording different classes of transactions, of means for determining the class of transaction to be recorded, an impression taking means coöperating with said type carriers, and devices coöperating with said determining means and adjustable at will for enabling or disabling the impression taking means.

49. In an accounting machine, the combination with type carriers for recording different classes of transactions, of manipulative means for determining the class of transaction to be recorded, an impression taking means coöperating with said type carriers, and an element controlled by said manipulative means and comprising elements removable at will to disable said impression taking means.

50. In an accounting machine, the combination with a plurality of accounting devices each designed to receive entries of a certain class, a common operating mechanism therefor, manipulative means for classifying entries in the accounting devices by establishing coöperative relation between the operating mechanism and the proper accounting device, type carriers, a normally inoperative means for taking impressions from said type carriers, and an element operated by the aforesaid manipulative means and carrying detachable devices for rendering said impression taking means operative.

51. In an accounting machine, the combination with a plurality of totalizers each designed to receive entries of a certain class, a set of actuators therefor, manipulative means for establishing coöperative relation between any desired totalizer and said actuators, type carriers, impression taking means coöperating with said type carriers, and an element operated by said manipulative means and carrying devices adjustable at will for controlling said impression means.

52. In an accounting machine the combination with type carriers for recording different classes of transactions upon a record material, of means for determining the class of the transaction to be recorded, a platen coöperating with said type carriers to take impressions on the record material, and devices adjustable at will coöperating with

said determining means for enabling or disabling the platen.

53. In an accounting machine the combination with type carriers for recording different classes of transactions upon a record material, of manipulative means for determining the class of transaction to be recorded, a platen coöperating with said type carriers to take impressions on the record material, and an element positioned by operations of said manipulative means and comprising elements removable at will to disable said platen.

54. In an accounting machine, the combination with a plurality of accounting devices each designed to receive entries of a certain class, a common operating mechanism therefor, manipulative means for classifying entries in the accounting devices by establishing coöperative relation between the operating mechanism and the proper accounting devices, type carriers, a normally inoperative platen for taking impressions from said type carriers, and an element operated by said manipulative means and carrying detachable devices for rendering said platen operative.

55. In an accounting machine, the combination with a plurality of totalizers each designed to receive entries of a certain class, a set of actuators therefor, manipulative means for establishing coöperative relation between any desired totalizer and said actuators, type carriers, a platen for taking impressions from said type carriers, and an element operated by said manipulative means and carrying devices adjustable at will for controlling said platen.

56. In an accounting machine, the combination with an operating mechanism comprising an invariably moved element, a differentially movable element, means for establishing connection between the invariably moved element and the differentially movable element, an adjustable lever, a series of keys, and means controlled by either said lever or said keys for disconnecting the differentially movable element from the invariably moved element.

57. In an accounting machine, the combination with an operating mechanism, of an element differentially moved thereby, and separate means for controlling said differential movement, either of said means being operable to stop the differentially moved element at the same position.

58. In a machine of the class described, the combination with setting means, of a series of clerks' keys, and means controlled by the setting means for locking all, some, or none of said keys according to the operation of said setting means.

59. In a machine of the class described, the combination with setting means, of a

series of clerks' keys, means controlled by the setting means for locking all, some, or none of said keys according to the operation of said setting means, and means preventing 5 operation of said keys during the operation of said setting means.

60. In a machine of the class described, the combination with setting means, of a series of clerks' keys, means controlled by 10 the setting means for locking all, some, or none of said keys according to the operation of said setting means, and means for preventing operation of said keys during the 15 operation of said setting means and for preventing operation of the setting means after a key has been operated.

61. In a machine of the class described, the combination with setting means, of a series of clerks' keys, and means controlled 20 by said setting means for locking certain or none of said keys according to the operation 25 of the setting means.

62. In a machine of the class described, the combination with setting means, of a series of clerks' keys, means controlled by 25 said setting means for locking certain or none of said keys according to the operation of the setting means, and means preventing 30 operation of the setting means after a key has been operated.

63. In a machine of the class described, the combination with setting means, of a series of clerks' keys, means controlled by said setting means for locking certain or 35 none of said keys according to the operation of the setting means, and means preventing the operation of both the setting means and the keys except in a predetermined sequence.

64. In a machine of the class described, 40 the combination with a differentially adjustable setting element, of a series of clerks' keys, and means controlled by said element for locking certain or none of said keys according to the adjustment of said element.

65. In a machine of the class described, 45 the combination with a differentially adjustable setting element, of a series of clerks' keys, means controlled by said element for locking certain or none of said keys according to the adjustment of said element, and means preventing operation of the keys 50 during the operation of said element.

66. In a machine of the class described, 55 the combination with a differentially adjustable setting element, of a series of clerks' keys, means controlled by said element for locking certain or none of said keys according to the adjustment of said element, and means for preventing operation of the keys 60 during the operation of said element and for preventing operation of said element after a key has been operated.

67. In a machine of the class described, 70 the combination with a differentially ad-

justable setting element, of a series of clerks' keys, means controlled by said element for locking certain or none of said keys according to the adjustment of said element, and means preventing the operation of both the setting means and the keys except in a pre- 70 determined sequence.

68. In a machine of the class described, the combination with a differentially adjustable setting element, of a series of clerks' keys, and means controlled by said element 75 for locking all, some, or none of said keys according to the adjustment of said element.

69. In a machine of the class described, the combination with a differentially adjustable setting element, of a series of clerks' 80 keys, means controlled by said element for locking all, some, or none of said keys according to the adjustment of said element, and means preventing operation of any of 85 said keys during the adjustment of said element.

70. In a machine of the class described, the combination with a differentially adjustable setting element, of a series of clerks' keys, means controlled by said element for 90 locking all, some, or none of said keys according to the adjustment of said element, and means for preventing operation of any of 95 said keys during the adjustment of said element and for preventing adjustment of the element after a key has been operated.

71. In a machine of the class described, the combination with a differentially adjustable manipulative device, of a series of 100 keys, and means controlled by said manipulative device while in a plurality of positions for preventing operation of certain keys and permitting the operation of the remainder, and while in other positions for permitting operation of said certain keys 105 and preventing operation of the remainder.

72. In a machine of the class described, the combination with a differentially adjustable manipulative device, of a series of 110 keys, means controlled by said manipulative device while in a plurality of positions for preventing operation of certain keys and permitting the operation of the remainder, and while in other positions for permitting operation of said certain keys and preventing 115 operation of the remainder, and means preventing operation of the keys during the adjustment of said manipulative device.

73. In a machine of the class described, the combination with a differentially adjustable manipulative device, of a series of keys, 120 means controlled by said manipulative device while in a plurality of positions for permitting operation of certain keys and preventing the operation of the remainder, and while in other positions for preventing operation of said certain keys and permitting 125 operation of the remainder, and means

for preventing operation of the keys during the adjustment of said manipulative device and for preventing adjustment of the manipulative device after a key has been operated.

74. In a machine of the class described, the combination with a differentially adjustable manipulative device, of a series of keys, means controlled by said manipulative device while in a plurality of positions for permitting operation of certain keys and preventing the operation of the remainder, and while in other positions for preventing operation of said certain keys and permitting operation of the remainder, and means for preventing the adjustment of the manipulative device and operation of the keys except in a predetermined sequence.

75. In a machine of the class described, the combination with a differentially adjustable manipulative device, of a series of keys, means controlled by said manipulative device while in a plurality of positions for permitting operation of certain keys and preventing the operation of the remainder, and while in other positions for preventing operation of said certain keys and permitting operation of the remainder, a main operating mechanism, and normally effective locking means for the operating mechanism, controlled by the keys and the manipulative devices, and constructed to effect the release of the operating mechanism only upon operation of the manipulative device and the keys in a predetermined sequence.

76. In a machine of the class described, the combination with setting means, of a series of keys, and means, controlled by said setting means, for preventing the operation of all but one of said keys and for preventing the operation of the previously unlocked key and permitting operation of the other keys according to the operation of the setting means.

77. In a machine of the class described, the combination with setting means, of a series of keys, means controlled by said setting means for preventing the operation of all but one of said keys and for preventing the operation of the previously unlocked key and permitting operation of the other keys according to the operation of the setting means, and means preventing the operation of a key during the operation of the setting means and for preventing the operation of the setting means after a key has been operated.

78. In a machine of the class described,

the combination with setting means, of a series of keys, means controlled by said setting means for preventing the operation of all but one of said keys and for preventing the operation of the previously unlocked key and permitting operation of the other keys according to the operation of the setting means, a main operating mechanism, and a normally effective locking means for the operating mechanism, constructed to effect the release of the locking mechanism only upon the operation of both the setting means and a key.

79. In a machine of the class described, the combination with setting means, of a series of keys, and means controlled by said setting means for locking all but one key, for unlocking a portion of the previously locked keys and locking the previously unlocked key, and for unlocking all of the first mentioned locked keys and locking the first mentioned locked key according to the operation of the setting means.

80. In a machine of the class described, the combination with setting means, of a series of keys, means controlled by said setting means for locking all but one key, for unlocking a portion of the previously locked keys and locking the previously unlocked key, and for unlocking all of the first mentioned locked keys and locking the first mentioned locked key according to the operation of the setting means, and means for preventing operation of the keys during the operation of the setting means and for preventing operation of the setting means after a key has been operated.

81. In a machine of the class described, the combination with setting means, of a series of keys, means controlled by said setting means for locking all but one key, for unlocking a portion of the previously locked keys and locking the previously unlocked key, and for unlocking all of the first mentioned locked keys and locking the first mentioned locked key according to the operation of the setting means, a main operating mechanism, and a normally effective locking mechanism, constructed to effect release of the main operating mechanism only upon operation of both a key and the setting means.

In testimony whereof I affix my signature in the presence of two witnesses.

EDWARD J. VON PEIN.
